(57) **CLAIM**

The ornamental design for a display screen or portion
thereof with graphical user interface, as shown and
described.

DESCRIPTION

Sole FIGURE is a front view of a display screen or portion
thereof with graphical user interface showing our new
design.

The outer perimeter shown in broken line in the FIGURE
illustrates a display screen or portion thereof and forms no
part of the claimed design. The remaining broken lines in the
FIGURE illustrate portions of the graphical user interface
that form no part of the claimed design.
